DESIGN FOR A SERVING GLASS FOR ICE CREAM SODAS OR THE LIKE

Morris Schneider, New York, N. Y.

Application July 15, 1936, Serial No. 63,851

Term of patent 14 years

To all whom it may concern:

Be it known that I, Morris Schneider, a citizen of the United States, residing at 926 Southern Boulevard, city of New York, county of Bronx, and State of New York, have invented a new, original, and ornamental Design for a Serving Glass for Ice Cream Sodas or the like, of which the following is a specification, reference being had to the accompanying drawing, forming a part thereof.

for ice cream sodas or the like showing my design.

I claim:

The ornamental design for a serving glass for ice cream sodas or the like as shown.

In testimony whereof I have signed this specification.

MORRIS SCHNEIDER.
